SHOE

Stanley E. Bishop, Cambridge, and Nathan J.
Lissak, New Bedford, Mass.

Application December 7, 1951, Serial No. 17,647

Term of patent 7 years

(Cl. D7—7)

To all whom it may concern:

Be it known that we, Stanley E. Bishop, a citizen of the United States and a resident of Cambridge, in the county of Middlesex and Commonwealth of Massachusetts; and Nathan J. Lissak, a citizen of the United States and a resident of New Bedford, in the county of Bristol and Commonwealth of Massachusetts, have invented a new, original, and ornamental Design for a Shoe, of which the following is a specification, reference being had to the accompanying drawing, forming a part hereof.

In the drawing:

Fig. 1 is a plan view of a shoe, showing our new design;

Fig. 2 is a side elevational view of the shoe; and

Fig. 3 is an elevational view of the opposite side of the shoe shown in Fig. 2.

We claim:

The ornamental design for a shoe, substantially as shown and described.

STANLEY E. BISHOP.
NATHAN J. LISSAK.
